UNITED STATES PATENT OFFICE

91,961

DESIGN FOR A WOVEN EDGING

Franklin W. Oehrle, Philadelphia, Pa., assignor to
Oehrle Brothers Company, Philadelphia, Pa.,
a corporation of Pennsylvania

Application February 1, 1934, Serial No. 50,577

Term of patent 7 years

To all whom it may concern:

Be it known that I, FRANKLIN W. OEHRL, a citizen of the United States, residing in Philadelphia, in the county of Philadelphia and State of Pennsylvania, have invented a new, original, and ornamental Design for a Woven Edging, of which the following is a specification, reference being had to the accompanying drawing, forming part thereof.

The figure is a plan view of a piece of woven edging showing my new design.

I claim:

The ornamental design for a woven edging, as shown.

In testimony whereof I have hereunto signed my name this 29th day of January, A. D. 1934.

FRANKLIN W. OEHRL.
